GAME APPARATUS AND CONTROL MEANS

Jerry C. Koci, Chicago, Ill., assignor to Chicago Coin Machine Mfg. Co., Chicago, Ill., a corporation of Illinois

Application September 21, 1938, Serial No. 231,007

15 Claims. (Cl. 273—138)

This invention relates to amusement apparatus and selective control means therefor, and has as one of its principal objects the provision of a game including a plurality of balls or analogous counters or playing pieces which are designed so as to have different characteristics, preferably with respect to size, and a selective detecting device and means for moving the balls or counters relative thereto, said selective detecting device being arranged and constructed to selectively arrange or dispose the balls or counters in predetermined positions in accordance with their various characteristics as aforesaid.

Another object is the provision of control means arranged for operation by the several balls or counters when the same are selectively disposed in the predetermined positions aforesaid, for controlling some instrumentality associated with the game.

Another object is the provision of a novel means for effecting movement of the balls or counters toward and into, or relative to, the selective detecting and control means.

Another object is the provision of a game in which there are a plurality of balls of different size and means for automatically arranging the balls according to size in predetermined positions, together with control means and operating means therefor arranged at the predetermined positions for operation by a ball which may have been selectively disposed at one of said positions.

Viewed from another aspect, it is an important object of the invention to provide a game apparatus including a playing board which is preferably inclined, a plurality of balls varying slightly in diameter and means for moving the balls relative to a selecting device which will cause the balls to be positioned in a certain manner in accordance with the diameter thereof, there being a control instrumentality, such for example as a switch, disposed at each position which may be occupied by a ball and there being some controlled instrumentality actuated in a predetermined manner by the several control devices depending upon the manner in which the balls are selectively positioned.

Other objects and novel aspects of the invention reside in certain details of construction, form, location, and operation of the parts hereinafter described in view of the annexed drawing in which:

Fig. 1 is a fragmentary top plan view of a game apparatus embodying the novel features of the invention;

Fig. 2 is an enlarged fragmentary perspective of the selecting means;

Fig. 3 is a fragmentary bottom perspective of the playing board and projecting control mechanism;

Fig. 4 is an enlarged fragmentary vertical section through the projecting mechanism as viewed along line 4—4 of Fig. 1;

Fig. 5 is a fragmentary vertical section to enlarged scale of one of the controlled instrumentalities in the nature of a signal, taken along line 5—5 of Fig. 1; while

Fig. 6 is a circuit diagram.

A preferred embodiment of the invention includes, as viewed in Fig. 1, a cabinet in which there is disposed a playing board 10 inclined slightly relative to the horizontal so that the balls or other counters or playing pieces may gravitate thereover. The playing pieces or counters in the present instance are balls approximately the size of large marbles, and the balls are preferably distinguished one from another by a characteristic color. The balls, as shown in Figs. 1 and 2, are lined for color and for convenience are designated serially I, II, III, IV, and V.

Means for effecting movement of the counters or balls over the playing board includes a plunger 11 mounted on a front wall 12 of the cabinet and a master control in the form of a plunger 13 which must be operated each time the game is played. The player pushes the control or plunger 13 inwardly and, as illustrated in Fig. 3, the inner end portion 14 of the master control plunger engages a flange 15 at one end of a lever 16 pivoted as at 17 on the under side of the board 10. At its opposite end the lever 16 is movably fitted into a stirrup 18 on an elongated plunger bar 19 which is mounted for reciprocation on the under side of the playing board by means of longitudinally spaced pins 20 working in slots 21 on the projector bar. A spring 22 is attached to one end of the bar 19 (see also Fig. 4) and urges the latter to move the opposite offset striker portion 23 thereof into forward position in a slot 24 cut in the board 10 just above the projecting plunger 11.

In order to operate the game, the player pushes the plunger 13 inwardly and pivots the lever 16 so as to move the projector bar 19 and tension the spring 22 thereof, with the result that the striker portion 23 of the projecting bar moves into the dotted line position shown in Fig. 4. At the same time the latching notch portion 30 of a latching pawl 31, which is pivoted as at 32 to a bracket on the under side of the playboard, is urged by the action of a spring 33, attached to a wing 34 on the pawl, so that the notch portion 30 is engaged over the edge of the lever 16 and holds the same and the projecting bar 19 in retracted position.

50

55

The inner end portion of the projecting plunger 11 passes through a slot 35 in the wing 34, and a collar 36 on the inner end of the plunger bears against the wing 34 when the plunger is withdrawn and trips the latching pawl 31 so that the projecting bar 19 is quickly snapped back to initial position by its spring 22, with the result that any of the counters or balls which may be resting against the offset striking portion 23 of the projecting bar, as in Fig. 4, will be projected out onto the board 10 for movement thereover, as will be described hereinafter. A suitable hood 37 may be arranged over the striker portion 23 to shield the same and the slot 24 from view.

The counters or balls, as heretofore pointed out, preferably have different characteristics and are differentiated one from another by their color and also in diameter, each ball differing from the next in size by a slight amount, for example 0.015 inch, for the purpose of cooperating with a ball detector or selecting device which is adapted to position the balls in a predetermined manner in accordance with their size, a particular size of ball being further distinguished by a corresponding color or other identifying expediency.

The means for selectively positioning the counters or balls includes the provision of a guideway or receptacle into which the balls are moved. In the illustrative arrangement, the guideway or receptacle is formed by a pair of spaced rails 40 and 41 (Figs. 1 and 2) mounted in nearly parallel relation on the top of the board 10, preferably near the lower end thereof, the rail 40 being relatively stationary and spaced from the top of the board a distance to bring it approximately at the center level of the several balls. The companion rail 41 is similarly spaced from the top of the board but is pivotally mounted on one of its mounting posts as at 42, the opposite end portion being supportably guided in a slotted cleat 43 rigidly secured to the play-board. By this arrangement the movable rail 41 may be pivoted to move the lower end portion thereof toward and away from the stationary rail 40. The lowermost end of the movable rail 41 is provided with a notch 44 adapted to bear against a stopping cleat 45 which accurately positions the movable rail in a predetermined spaced relation to the stationary rail. A leaf spring 46 secured as at 47 to a raised member on the playing board 10 urges the rail 41 into such normal position.

When the movable rail 41 is in its normal position due to the action of the spring 46 limited by the stop 45, the rods 40 and 41 are spaced apart slightly more at their upper (right-hand) ends than at the lower ends, and this spacing, which may be accomplished simply by regulating the relative pitch of the movable member 41 with respect to the member 40 or by the provision of a slanted edge portion on one or both of the members, as desired, is such that the counters or balls will become wedged between the rails in sequentially spaced relation, as viewed in Fig. 1, provided the balls pass in between the rails in the sequential order of the variation of diameter. Thus, the ball having the smallest diameter and designated I, if it enter between the rails first, may pass to the bottommost ends thereof but not beyond, due to the substantially wedging action which results from spacing the rails as aforesaid. Assuming the ball having the next largest diameter and designated II enters between the rails immediately following

ball I, it will become lodged at the next higher level in spaced relation to the first ball, and if the succeeding balls all enter between the rails in the order of their increasing diameter, they will all be similarly spaced. In this manner the 5 balls or counters are selectively positioned, and when the balls enter the selecting guideway or means in proper sequence, the color scheme will be distributed for visual indication in accordance with a predetermined plan, the first ball, 10 for example, being red; the second, white; the third, yellow; the fourth, brown; and the fifth, blue, as indicated in Fig. 1, such an arrangement providing a visual indication to the player that he has achieved a winning combination or score. 15

Selective control means are associated with the detecting device heretofore described, and in the present arrangement this means includes a plurality of control members in the form of leaf spring switches 51, 52, 53, 54, and 55, each 20 having a contact spring constituting a finger extension 50 which is arranged to project at an angle into the passageway defined by the rails 40 and 41 so as to be operatively engaged by a corresponding one of the balls when the same 25 are disposed in their predetermined positions. Thus, the finger portion 50 of switch 51 will be engaged and operated by ball I which has the smallest diameter, provided ball I is the first to enter between the rails. Likewise, switch 52 30 will be operated by ball II, provided this ball enters the rails before ball III. Thus, it is possible that all of the switches or control devices may be operated in sequence, or only certain of the switches may be operated, depending upon 35 the order in which the balls enter the selecting device.

In Fig. 2, the blue ball V has entered between the rails first and as a consequence all of the remaining balls are piled up behind ball V and 40 prevented thereby from entering between the rails, with the result that only switch 55 can be operated in this instance.

A further feature of the game is the provision 45 of a controlled instrumentality or means in the nature of signal devices operated by the several switches. In the present arrangement, there are five lamps 61, 62, 63, 64, and 65 suitably mounted as by brackets 66 so as to project through openings 67 in the board and aligned correspondingly 50 with the serial alignment of the balls between the selecting rails. Each lamp is provided with a colored window or cap 61', 62', etc., the color of which corresponds in reverse order to the serial alignment of the colored balls. Thus, assuming that the red ball I were the first to enter the runway or receptacle, the lamp 61 at the farther right-hand end of the group of lamps 55 would be the first to be illuminated, and so on for the remaining balls. 60

A circuit arrangement for the selectively operable control devices and the controlled means is shown in Fig. 6 wherein each of the lamps 61, 62, 63, 64, 65 is connected to a common conductor 68 which in turn is connected through a time switch 69 to one side of a power source or battery 70, the return side of the battery being connected to a conductor 71 which is common to all of the spring contacts 50 of the several switches, the remaining contacts of which are 65 connected by conductors 72 to the other sides of the several lamps. The switch 69 may be closed by operation of the plunger 13 and will remain closed a predetermined period of time 70 and thereafter automatically opened so as to ex- 75

tinguish any of the lamps which may have been illuminated by the previous player.

Means for effecting removal of the balls from operative engagement with the selecting or detecting device includes the provision of a depending finger 80 (Figs. 2 and 3) on the lower end of the movable rail 41, which finger extends through a slot in the playboard 10 for engagement with a lateral extension or arm 81 on the lever 16. Each time the plunger 13 is operated to set the game for play, the arm 81 will engage the member 80 and pivot the movable rail member 41 in a direction away from the companion rail 40 a distance adequate to permit all of the balls to gravitate on down to the lower end of the playboard, the arrangement being such that the balls move thusly in position before an automatic projecting device 85 which is actuated each time a ball engages the same and projects the ball along a guideway 86 terminating in front of the hood 37 so that the balls will be serially aligned against the striker 23. Thereafter the player pulls the plunger 11 and effects projection of the entire group of balls out onto the board in the manner heretofore described.

In order to operate the device, the plunger 13 is first actuated to set the projecting bar 19 and move the rail 41 so that any balls between the rails may gravitate one by one into position before the automatic projector 85. As each ball gravitates against the projector 85, the latter operates automatically to propel the ball around the guideway 86 into a position in front of the striker 23 on the bar 19. When all of the balls have been aligned in front of the striker as aforesaid, the player withdraws the plunger 11, thus tripping the catch 31 and permitting the spring 22 to drive the bar 19 back to its initial position, with the result that the offset striker 23 will propel the entire group of balls along the raceway 25 toward the upper end of the board 10, the balls thereafter gravitating toward the mouth or upper end of the detecting or selecting means 40-41, and the balls being aligned in the latter to operate one or more of the control devices 51, 52, etc. for the purpose of operating the signal means or lamps 61, etc., to indicate achievement of one or another score depending upon the manner in which the balls are selectively positioned between the rails 40 and 41, the color scheme of the indicating means corresponding to that of the balls so that the relative score of the player is quickly and easily visualized.

Various modifications and rearrangements with respect to the form, location, and operation of the illustrative device described herein may be made without departing from the scope of the invention as defined in the appended claims, all of which expressly include all equivalent arrangements.

Having thus described my invention, what I claim as new and desire to protect by Letters Patent is:

1. In combination, means providing an inclined ball playing surface, a plurality of balls of different diameters, means for effecting movement of said balls over said surface, selecting mechanism including spaced members arranged on said surface so that said balls may move therebetween, said spaced members being arranged each with respect to the other so that said balls will be stopped at predetermined locations therebetween depending upon the diameter of the ball, and means for moving one of said

members relative to the other to permit all of said balls to gravitate from between the same.

2. In combination, means providing an inclined ball playing surface, a plurality of balls of different diameters, means for effecting movement of said balls for gravitation from the upper end of said board toward the lower end thereof, and selecting means including longitudinally spaced members arranged on said board so that said balls may gravitate therebetween, said spaced members being arranged and constructed so that the distance therebetween decreases at intervals from the uppermost toward the lowermost ends thereof whereby said balls may be arrested at certain spaced positions between said members depending upon the diameter of the balls, and means for moving one of said spaced members relative to the other to permit all of said balls to gravitate therebetween and therepast.

3. In combination, means providing an inclined ball playing surface, a plurality of balls of different diameters, means for effecting movement of said balls for gravitation from the upper end of said board toward the lower end thereof, and selecting means including longitudinally spaced members arranged on said board so that said balls may gravitate therebetween, said spaced members being arranged and constructed so that the distance therebetween decreases at intervals from the uppermost toward the lowermost ends thereof whereby said balls may be arrested at certain spaced positions between said members depending upon the diameter of the balls, and means for moving one of said spaced members relative to the other to permit all of said balls to gravitate therebetween and therepast, and control means in the form of a plurality of switches each having an operating member arranged at one of said certain positions for engagement and operation by a ball selectively disposed at the corresponding position as aforesaid, together with signal means operatively associated with each of said switches for indicating the relative disposition of balls at said certain positions.

4. In combination, means providing an inclined ball playing surface, a plurality of balls of relatively diminishing diameters, means for effecting movement of said balls from the upper toward the lower end of said surface, and selecting means including a pair of rail members and means mounting the same on said surface in spaced relation with the length of said rails extending in the direction of inclination of said surface, said rails defining a passageway having an entrance end at the uppermost end of said rails and an exit end at the lowermost end thereof, said rails being spaced apart diminishing distances from said upper toward said lower end whereby said balls will be arrested between said rails at certain positions where the distance between the rails is slightly less than the diameter of one of said balls, one of said rails being movable relative to the other, means for effecting movement of said movable rail to widen the distance between the same and the remaining rail whereby all of said balls may be permitted to gravitate from between the rails out said exit end.

5. In combination, means providing an inclined ball playing surface, a plurality of balls of relatively diminishing diameters, means for effecting movement of said balls from the upper toward the lower end of said surface, and selecting means including a pair of rail members

and means mounting the same on said surface in spaced relation with the length of said rails extending in the direction of inclination of said surface, said rails defining a passageway having 5 an entrance end at the uppermost end of said rails and an exit end at the lowermost end thereof, said rails being spaced apart diminishing distances from said upper toward said lower end whereby said balls will be arrested between said 10 rails at certain positions where the distance between the rails is slightly less than the diameter of one of said balls, one of said rails being movable relative to the other, means for effecting movement of said movable rail to widen the distance between the same and the remaining rail 15 whereby all of said balls may be permitted to gravitate from between the rails out said exit end, and a plurality of switches each having an actuating element disposed at a predetermined 20 position relative to said passageway, and corresponding to the position of arrest of one of said balls, for engagement and operation by the corresponding ball, together with controlled means arranged for operation by said switches dependent upon the relative distribution of balls in said 25 passageway.

6. Game apparatus including means providing a confined ball playing area, a plurality of balls of different diameters, means for effecting 30 movement of said balls in a particular direction in said area, and ball selecting means including means defining an elongated ball passage, the length of which extends substantially in the same direction as said particular direction, said 35 passage being of different width at different points therealong from one end toward the other so that certain balls will be arrested at certain positions in the passage depending upon the relative diameter of the ball and width of said 40 passage at said positions, and control means arranged for engagement and operation by one of said balls at one or more of said selected positions, together with mechanism cooperable with said means defining the passage for widening the latter to permit all balls to pass freely there- 45 through in said particular direction.

7. Game apparatus including means providing an inclined ball playing board, a plurality of balls of different diameters and means for projecting 50 said balls toward the upper end of said board to effect gravitating movement of the same toward the lower end of the board, and ball selecting means including spaced members extending in the direction of inclination of said board so as to 55 define a ball passage having an entrance end at a higher level and an exit end at a lower level, one of said members being pivotally mounted near said entrance end for movement toward and away from the other said member, yieldable 60 means normally urging said movable spaced member toward said other spaced member, means normally limiting the movement of said movable member so as to stop the latter in a predetermined relation with said other member, the 65 distance between said members decreasing in a predetermined manner in a direction from said entrance toward said exit end for the purpose of arresting said balls at predetermined positions in said passage dependent upon their diameter 70 and the sequence in which said balls move into the passage as aforesaid, switch means arranged at one or more of said predetermined positions for engagement and operation by a ball arrested as aforesaid, and signal means arranged for 75 actuation by said switch means to indicate the

arrest of a ball at any of said predetermined positions.

8. Ball selecting mechanism for use in bagatelle games and the like, said selecting mechanism including a pair of spaced rails arranged to define a ball passage, one of said rails being arranged to move relative to the other to widen said passage, means normally urging said movable rail into an initial position relative to the remaining rail, the distance between said rails in normal position aforesaid varying at predetermined positions between the ends of said passage, a plurality of balls of different diameters for use in said game, one or more of said balls being moved into said passage as a result of playing the game, certain balls being arrested at certain positions in the passage dependent upon the diameter of a given ball, and means for effecting movement of the movable rail to widen the passage and free an arrested ball for movement out of the passage. 10 15 20

9. Ball selecting mechanism for use in game apparatus of the type including ball projecting means for effecting movement of balls over an inclined playing board, said selecting mechanism 25 comprising: spaced members defining a ball passage having an entrance at a higher level and an exit at a lower level, one of said members being movable relative to the other, yieldable means normally urging the movable member into a predetermined normal position relative to the other member, mechanism operable to effect movement of said movable member to widen said passage for unrestricted movement of balls there- 30 through, the width of the passage between said members varying at different points therealong when the members are in normal position as aforesaid, and a plurality of balls of different diameters for use in said game, said balls being arrested at predetermined positions along said 35 passage when said members are in normal position in a manner determined by the relative diameter of a given ball and the width of said passage at a predetermined position, and control means arranged along said passage at positions corresponding to positions of arrest of said 40 balls so as to be engaged and operated by an arrested ball, and means arranged for selective actuation by said control means dependent upon the arrest of balls at various positions in the 45 passage. 50

10. Selective control means for use in a ball playing apparatus of the type including an inclined playing field and means for projecting balls onto said field for gravitating movement 55 thereover, said selective control means comprising: spaced rail members defining an elongated passage extending in the direction of inclination of said field and having an entrance at a higher level and an exit at a lower level, one of said 60 rails being arranged for movement in a direction toward and away from the remaining rail, means normally urging the movable rail into a predetermined spaced relation with the remaining rail, means for moving the movable rail away 65 from the remaining rail, the distance between said rails in normal relation diminishing in a predetermined manner from the entrance toward the exit thereof whereby to provide a passageway of diminishing width, a plurality of balls for use in said game, said balls differing in diameter one relative to another in a predetermined order and being adapted to be projected by the aforesaid projecting means for movement into said passageway, said balls being arrested at certain positions 70 75

in the passageway according to their diameter and the width of said passage at said positions, switch means arranged for operation by arrested balls at predetermined positions of arrest along 5 the passageway, and a plurality of electrically operated indicators arranged for operation to designate certain positions of arrest of balls in the passageway and each actuated by one of said switch means whereby the distribution of arrested balls in said passageway may be indicated, said movable rail being movable as aforesaid away from the remaining rail to free arrested balls for gravitation out of the passageway.

11. Selective control means for use in a ball 15 playing apparatus of the type including an inclined playing field and means for projecting balls onto said field for gravitating movement thereover, said selective control means comprising: spaced rail members defining an elongated 20 passage extending in the direction of inclination of said field and having an entrance at a higher level and an exit at a lower level, one of said rails being arranged for movement in a direction toward and away from the remaining rail, 25 means normally urging the movable rail into a predetermined spaced relation with the remaining rail, means for moving the movable rail away from the remaining rail, the distance between said rails in normal relation diminishing in a predetermined manner from the entrance toward the exit thereof whereby to provide a passageway of diminishing width, a plurality of balls for use in said game, said balls differing in diameter one relative to another in a predetermined order 30 and being adapted to be projected by the aforesaid projecting means for movement into said passageway, said balls being arrested at certain positions in the passageway according to their diameter and the width of said passage at said 40 positions, control means arranged for operation by balls in said positions, a plurality of signal lamps arranged for operation by said control means to designate predetermined positions of arrest of balls in said passage, each ball being 45 provided with indicia which corresponds to designating indicia characterizing one of said lamps, the arrangement being such that the arrest of a given ball at a predetermined position in said passageway will effect energization of the corresponding lamp through the agency of said control means, the designating indicia of said ball and lamp corresponding and the lamps therefore being operable to indicate the relative 50 positions of such balls as are arrested in the passageway, said movable rail being movable as aforesaid to widen the passage and permit all of said balls to gravitate out of the same.

12. In a device of the class described, ball selecting means including spaced members defining a descending ball passage having an entrance end at a higher level and an exit end at a lower level, said passage diminishing in width at predetermined points from said entrance toward said exit end so as to arrest balls of predetermined 55 diameter arriving at said predetermined points along the passage, a plurality of balls of different predetermined diameters for movement into and arrest in said passage as aforesaid, control means arranged at said predetermined 60 positions along the passage for engagement and

operation by balls arrested at said positions, and apparatus operably controlled by said control means, and means for moving one of said spaced members relative to the other and thereby permit gravitation of any arrested balls out said 5 exit end.

13. In a sorting mechanism adapted for use with spherical objects of different diameter, spaced members arranged to define a passage in which said spherical objects may be serially 10 aligned, one of said spaced members extending at an angle with respect to the other in a convergent sense whereby the distances across the passage will vary between the opposite ends thereof, said spherical objects being arrested at certain 15 positions along the passage in accordance with their respective diameters, one of said members being mounted for movement out of a normal position with respect to the other said member to widen said passage and permit all of said 20 objects to pass therethrough.

14. In a sorting mechanism adapted for use with spherical objects of different diameter, spaced members arranged to define a passage in which said spherical objects may be serially 25 aligned, one of said spaced members extending at an angle with respect to the other in a convergent sense whereby the distances across the passage will vary between the opposite ends thereof, said spherical objects being arrested at certain 30 positions along the passage in accordance with their respective diameters, one of said members being mounted for movement out of a normal position with respect to the other said member to widen said passage and permit all of said objects to pass 35 therethrough, together with control means arranged for selective operation by a desired one of said spherical objects and including an actuating part disposed at the aforesaid particular position corresponding to the position occupied by 40 the desired object in said passage for engagement and operation by said object when the same is disposed in said position.

15. Ball selecting apparatus and signaling means including spaced members defining a ball 45 passage having an entrance and an exit end and in which a series of balls of different diameters may be aligned, the distance across said passage diminishing from the entrance end toward the exit end thereof in such manner that said balls will be aligned in the order of their diameters, one of said members being movable from a normal position away from the other to widen 50 said passage and permit all of said balls to move out of the same from said exit end, each of said balls being provided with characteristic indicia, an indicating device for each of said balls and provided with indicia means correlating the same with the indicia of a particular ball, and selectively operable control mechanism for said indicating devices and including a plurality of control operating members each arranged at predetermined 55 positions along said passage for operative engagement by a certain ball disposed thereat in the manner aforesaid to actuate the corresponding indicating device, whereby the distribution of said balls in said passage may be indicated.
